(57) **CLAIM**

We claim the ornamental design for a power generator information unit, as shown and described.

DESCRIPTION

FIG. 1 is a perspective view of a power generator information unit according to our invention;

FIG. 2 is a front view of the power generator information unit of FIG. 1;

FIG. 3 is a rear view of the power generator information unit of FIG. 1;

FIG. 4 is a right side view of the power generator information unit of FIG. 1;

FIG. 5 is a left side view of the power generator information unit of FIG. 1; and,

FIG. 6 is a top view of the power generator information unit of FIG. 1.

The broken lines showing the environment are for illustrative purposes only and form no part of the claimed design.
